H. H. Styll, A. W. Parsons
ATTORNEYS

UNITED STATES PATENT OFFICE.

GEORGE H. DAY, OF SOUTHBRIIDGE, MASSACHUSETTS, ASSIGNOR TO AMERICAN OPTICAL COMPANY, OF SOUTHBRIIDGE, MASSACHUSETTS, A VOLUNTARY ASSOCIATION OF MASSACHUSETTS.

EYE-PROTECTOR.

1,340,701.

Specification of Letters Patent. Patented May 18, 1920.

Application filed January 25, 1917. Serial No. 144,404.

To all whom it may concern:

Be it known that I, GEORGE H. DAY, a citizen of the United States, residing at Southbridge, in the county of Worcester and State 5 of Massachusetts, have invented certain new and useful Improvements in Eye-Protectors, of which the following is a specification.

This invention relates to improvements in eye protectors, and has particular reference to an improved construction of light 10 weight eye protector particularly adapted for motoring or similar use.

One of the leading objects of the present invention is the provision of an improved 15 construction of rim or lens frame member which shall satisfactorily retain the lens in position, which shall be comfortable in its fit against the face of the wearer, and which shall be provided with means facilitating 20 the ready attachment of a lateral shield when desired.

Other objects and advantages of my improved construction should be readily apparent by reference to the following specification taken in connection with the accompanying drawings, and it will be understood that I may make any modifications in the 25 specific details of construction shown and described within the scope of the appended 30 claims without departing from or exceeding the spirit of my invention.

Figure I represents a plan view of a complete protector constructed in accordance with and embodying my invention.

Fig. II represents a horizontal sectional view through one of the lens frames.

Fig. III represents a plan view of the blank from which my improved construction is formed.

Fig. IV represents a plan view showing a folding screen member attached to my improved rim.

Fig. V represents a vertical sectional view of my construction with the parts in folded 45 relation.

In the drawings, in which similar characters of reference are employed to denote corresponding parts throughout the several views, the numeral 1 denotes the bridging 50 member, serving to connect my improved rim, which retains in position the usual eye protecting lenses 2.

My improved rim, as is most clearly illus-

trated in Fig. III, comprises a single strip of material beveled at the end at the points 55 3, and having the additional pair of cuts or notches 4 formed therein at points substantially half way between the center and end of the rim. The rim in this form is then rolled to form at one edge the V-shaped 60 groove 5 adapted to receive and secure in position the beveled edge of the lens 2.

At the opposite edge my improved rim is rolled as respects the central portion included between the notches 4 to provide the 65 rounded bead 6 adjacent the face, while the remaining portion is left upstanding in the projecting flange portion 7, preferably provided with the apertures 8 adapted to receive rivets 9 for securing in position the 70 leather or flexible shield member 10, although it will be understood that if desired the rivets 9 may be employed to pivotally or otherwise secure in position the rigidly attached folding screen member 11, 75 illustrated in Fig. IV.

At the connecting ends of my improved rim I provide the usual end pieces 12, in which are pivoted the temples 13 extending rearwardly as through the slot 14 formed in 80 the flexible protector 10.

By reference particularly to Fig. V the purpose or function of the beveled portions 3 should be readily apparent, and it will 85 be seen that when the end pieces 12 are secured together the beveled portions together form a substantially V-shaped cut at the outer edge of the rim adjacent the point of pivotance of the temple, and that consequently when it is desired to swing the 90 temple downward into folded position, the flexible shield member 10 and temple will crush inward into the V-shaped notch thus provided, and in this manner a much more compact folding of the parts is accomplished 95 than has hitherto been possible.

From the foregoing description taken in connection with the accompanying drawings, the construction of my improved rim should be readily apparent, and it will be 100 seen that I have provided a simple and efficient construction which may be readily manufactured, which provides a satisfactory hold for the desired shield member, which permits of ready folding of the shield member 105 into closed position as desired, and in

which the non-shield-bearing portion is so shaped as to provide a soft and comfortable face engaging portion.

I claim:

- 5 1. A blank for an eye protector rim comprising a single strip of material having notches formed in one edge at points intermediate the center and ends of the strip and having the opposite edge bent into V-shape
- 10 10 in cross section to provide a lens receiving groove, the central portion of the ungrooved edge intermediate the notches being rolled to provide a face receiving bead and the terminal portions being adapted to be connected and project beyond the bead in a flange, said flange portion having a plurality of apertures formed therethrough, substantially as and for the purpose described.
- 15 2. In an eye protector, the combination with a lens, of a retaining rim therefor, having a groove to receive the lens, and a rearwardly extending portion, said portion having a plurality of indentations formed in the rear face thereof, the edge of the protector between certain of the indentations being rolled to form a face engaging seat, and
- 20 25 between certain of the other indentations being extended to form a screen receiving flange, an end piece carried by the rim and disposed adjacent one of the indentations in the rear edge thereof, and a temple carried by the end piece and adapted to fold into the indentation in the flange, substantially as illustrated.
- 25 3. A blank for an eye protector rim comprising a single strip of material having notches formed in one edge at points inter-

mediate the center and ends of the strip and having the opposite edge bent into V-shape in cross section to provide a lens receiving groove, the central portion of the ungrooved edge intermediate the notches being rolled 40 to provide a face receiving bead and the terminal portions being adapted to be connected and project beyond the bead in a flange, said flange portion having a plurality of apertures formed therethrough, substantially 45 as and for the purpose described.

4. An eye protector rim comprising a single strip of material having notches formed in one edge at points intermediate the center and ends of the strip and having 50 the opposite edge bent into V-shape in cross section to provide a lens receiving groove, the central portion of the ungrooved edge intermediate the notches being rolled to provide a face receiving bead and the terminal 55 portions being adapted to be connected and project beyond the bead in a flange, said flange having ventilation apertures formed therethrough and hollow open ended rivets engaged in the apertures, and a shield member pierced and secured in position on the flange by the hollow rivets whereby the rivets afford both shield attaching means and ventilation patches.

In testimony whereof I affix my signature 60 in the presence of two witnesses.

GEORGE H. DAY.
